US00D628385S

(12) **United States Design Patent**
Klein et al.

(10) **Patent No.:** US D628,385 S
(45) **Date of Patent:** ** *Dec. 7, 2010

(54) **CONTAINER**

(75) Inventors: **Richard B. Klein**, Overland Park, KS (US); **Mark A. Etter**, Independence, MO (US); **Brian Everett**, Shawnee, KS (US)

(73) Assignee: **Lynk, Inc.**, Shawnee Mission, KS (US)

(**) Term: **14 Years**

(21) Appl. No.: **29/351,811**

(22) Filed: **Dec. 11, 2009**

(51) **LOC (9) Cl.** 03-01

(52) **U.S. Cl.** D3/306

(58) **Field of Classification Search** D3/304-314; D19/75, 78, 86, 90, 91, 99, 100; D6/566, D6/567, 569, 512, 553, 525, 514; 211/10, 211/11, 13.1, 45, 50, 52, 55, 87.01, 90.03, 211/126.9, 126.13, 88.01, 41.4, 86.1, 134, 211/126.1, 181.1; 220/456, 9.4, 6.7, 600, 220/485, 488; 206/202, 513, 577

(57) **CLAIM**

The ornamental design for a container, as shown and described.

DESCRIPTION

FIG. 1 is an isometric view of a container embodying the design, with container brackets being shown in broken lines for illustrative purposes only and forming no part of the claimed design;

FIG. 2 is front elevation view of the container of FIG. 1 and again illustrating the container brackets in broken lines for illustrative purposes only so as not to form any part of the claimed design;

FIG. 3 is a side elevation view of the container of FIG. 1, with the opposite side elevation view being essentially a mirror image thereof, and further illustrating the container brackets in broken lines for illustrative purposes only so as not to form any part of the claimed design;

FIG. 4 is a rear elevation view of the container of FIG. 1 and illustrating the container brackets in broken lines for illustrative purposes only so as not to form any part of the claimed design;

FIG. 5 is a top-down plan view of the container of FIG. 1 and illustrating the container brackets in broken lines for illustrative purposes only so as not to form any part of the claimed design; and,

FIG. 6 is a bottom-up plan view of the container of FIG. 1 and illustrating the container brackets in broken lines for illustrative purposes only so as not to form any part of the claimed design.
